LOUIS BRUMBACH, OF READING, PENNSYLVANIA.

Letters Patent No. 77,249, dated April 28, 1868.

IMPROVEMENT IN MACHINE FOR WOOL-BURRING.

The Schedule referred to in these Letters Patent and making part of the same.

TO ALL WHOM IT MAY CONCERN:

Be it known that I, LOUIS BRUMBACH, of Reading, Pennsylvania, have invented an Improvement in Wool-Burring Machines; and I do hereby declare the following to be a full, clear, and exact description of the same.

My invention consists of a receptacle, hinged to the frame, and arranged, in respect to the toothed roller and slatted roller of a wool-burring machine, substantially as described hereafter, so that the said receptacle can be raised by the burrs as they are carried round with the wool by the toothed roller, but will fall before the burrs are acted upon by the slatted roller, the receptacle being thus in a position to receive the burrs forced from the wool by the slatted roller, and preventing them from falling on to the wool as it is being carried round by the toothed roller.

The advantage of my improvement is not only the thorough removal of the burrs from the wool, but the reduction of the speed of the slatted roller, as more fully explained hereafter.

In order to enable others skilled in the art to make and use my invention, I will now proceed to describe its construction and operation, reference being had to the accompanying drawing, which forms a part of this specification, and in which—

Figure 1 is a vertical section of my improved wool-burring machine, and

Figure 2 a plan view.

The side-frames A and A' of the machine are connected together by suitable cross-bars *a a*, and the platform *b*. In the said side-frames the feed-rollers B and B' are caused to turn in the direction of their arrows, and the rollers D and E in the direction of their arrows. The roller D is composed of a number of metal disks *d*, with teeth on their peripheries, somewhat similar to those of circular saws, the disks having distance-pieces between them of such a diameter as to leave the teeth exposed, and the whole being secured together, so as to form a substantial toothed roller.

The roller E has a number of bars or slats, *e*, of metal, the outer edges of which revolve very closely to, but not in absolute contact with, the teeth of the roller D.

The above-described mechanism is similar to that of ordinary wool-burring machines, the wool being fed over and in contact with the platform *b* to the two rollers B and B', after passing between which it is seized by the teeth of the roller D, which open and carry round the fibres of the wool and expose the burrs, and the latter being acted upon by the rapidly-revolving slatted roller E, are discharged into any suitable receptacle.

In ordinary wool-burring machines, the discharge of the burrs from the wool is, for the most part, dependent upon the rapidity with which the slatted roller E revolves, but even rapidity of revolution does not effectually prevent the burrs from striking the edge of the receptacle, which is always a short distance above the fleece, and thence falling on to the toothed roller D, and becoming again entangled with the wool as it is being carried round by the same.

In order to obviate this evil, I make use of a receptacle or trough, G, which is hinged at *x* to the frames A and A' of the machine, the bottom, *h*, of the receptacle, at and near the front end of the same, being shaped to conform to the toothed circumference of the roller D, with which it is nearly in contact, absolute contact being prevented by lugs *i i*, secured to the frame, on which lugs the receptacle rests.

The receptacle is almost balanced, the preponderance being in front, so that the front edge rests upon the fleece, and in close contiguity with the teeth of the roller D at all times, excepting when a burr is carried round with the wool, in which case the burr slightly raises the front of the receptacle. The latter falls, however, the instant the burr has passed it, and before it can be struck by the slats of the revolving roller E, so that the burr cannot strike the edge of the receptacle, which is always in a position to receive the burr, and prevent it from falling on to the wool carried round by the roller D.

By the use of the above-described improvement, the roller E may be reduced in speed, as the effective disposal of the burrs is not dependent upon its rapid revolution, but upon the self-adjusting receptacle G, which is always in a position to catch the burrs.

I claim as my invention, and desire to secure by Letters Patent—

The receptacle G, arranged in respect to the slatted and toothed rollers of a wool-burring machine, as described, and so balanced that it will be raised by a burr carried beneath it, and will fall with its edge in contact with the fleece before the slatted roller strikes the burr, all as and for the purpose described.

In testimony whereof, I have signed my name to this specification in the presence of two subscribing witnesses.

LOUIS BRUMBACH,
